Primary Examiner — Garth Rademaker*Assistant Examiner* — Katie Stofko Mroczka(74) *Attorney, Agent, or Firm* — Judy Jarecki-Black; Chad Kitchen; Merial Inc.(57) **CLAIM**

The ornamental design for an animal chew, as shown and described.

DESCRIPTION

FIG. 1 is a perspective view of an animal chew showing the new design;

FIG. 2 is a front elevation view, the rear elevation view being a mirrored image thereof; and,

FIG. 3 is a right side elevation view, the left side elevation view being identical thereto.

The break lines shown in the middle portion of the animal chew in FIGS. 1 and 2 indicate that the appearance of any portion of the article between the break lines forms no part of the claimed design.
